US00D837783S

(12) **United States Design Patent** (10) **Patent No.:** **US D837,783 S**
(45) **Date of Patent:** **** Jan. 8, 2019**

(54) **WEARABLE MOBILE COMPUTING DEVICE**

(71) Applicant: **Quanta Computer Inc.**, Taoyuan (TW)

(72) Inventors: **Jui-Lung Wang**, Taoyuan (TW);
Chu-Fu Wang, Taoyuan (TW);
Chang-Ta Miao, Taoyuan (TW);
Gwo-Chyuan Chen, Taoyuan (TW)

(73) Assignee: **QUANTA COMPUTER INC.**,
Guishan Dist., Taoyuan (TW)

(**) Term: **15 Years**

(21) Appl. No.: **29/567,160**

(22) Filed: **Jun. 6, 2016**

(30) **Foreign Application Priority Data**

Apr. 18, 2016 (TW) 105301984

(51) **LOC (11) Cl.** **14-02**

(57) **CLAIM**

The ornamental design for a wearable mobile computing device, as shown and described.

DESCRIPTION

FIG. 1 is a front perspective view of a wearable mobile computing device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is another front perspective view thereof.

The broken lines in the drawings depict portions of the wearable mobile computing device that form no part of the claimed design.

1 Claim, 8 Drawing Sheets
